CLAIM

The ornamental design for an electronic display panel for aircraft parking systems at airports, as shown and described.

DESCRIPTION

FIG. 1 is a front elevational view of an electronic display panel for aircraft parking systems at airports showing my new design;

FIG. 2 is a right side elevational view thereof, with the opposite side being a mirror image;

FIG. 3 is a rear elevational view thereof;

FIG. 4 is a top plan view thereof;

FIG. 5 is a bottom plan view thereof; and,

FIG. 6 is a perspective view thereof.

FIG. 1**FIG. 2****FIG. 3****FIG. 4****FIG. 5**FIG. 6
